United States Patent [19]

Brickner, Jr. et al.

[11] Patent Number: Des. 295,823

[45] Date of Patent: ** May 24, 1988

[54] COMBINED CIRCULAR SAW AND
MITERBOX UNIT

[75] Inventors: Louis C. Brickner, Jr., Pittsburgh,
Pa.; Jerry D. Skipworth, Burkesville,
Ky.; Steven W. Ashworth, Blawnox,
Pa.

[73] Assignee: Delta International Machinery Corp.,
Pittsburgh, Pa.

[**] Term: 14 Years

[21] Appl. No.: 846,544

[22] Filed: Apr. 3, 1986

[52] U.S. Cl. D8/66; D8/71

[57] CLAIM

The ornamental design for a combined circular saw and miterbox unit, substantially as shown.

DESCRIPTION

FIG. 1 is a top front and left side perspective view of a combined circular saw and miterbox unit showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and

FIG. 7 is a bottom plan view thereof.
